[57] CLAIM

The ornamental design for a carrier for compressed gas tanks and the like, as shown and described.

DESCRIPTION

FIG. 1 is a perspective view of a carrier for compressed gas tanks and the like showing my new design in its operating position relative to a compressed gas tank which is shown in dotted lines for illustrative purposes only;

FIG. 2 is an enlarged scale front elevational view thereof in its inoperative position;

FIG. 3 is a rear elevational view thereof;

FIG. 4 is a side elevational view thereof, the side not shown being a mirror image of the side shown;

FIG. 5 is a top plan view thereof; and,

FIG. 6 is a bottom view thereof.

FIG. 1
